UNITED STATES PATENT OFFICE

PHILIP PALMGREEN, OF MCKEESPORT, PENNSYLVANIA

AUXILIARY VALVE TOOL

Application filed August 21, 1928. Serial No. 301,063.

In removing the valves from internal combustion engines special tools, known as "valve spring lifters" are employed for compressing the valve spring and raising the washer to permit the removal of the cross-pin or other stop. These stops are usually simply pins which extend through diametric holes in the valve stem.

In these cases all that is necessary is to use the lifter to compress the spring and raise the washer off the pin, and the pin may then be driven out.

However, in some makes of internal combustion engines, a different form of stop is used, the lower end of the valve stem being provided with a circumferential groove and a pair of jaw members being associated with the washer in such a manner that the expansion of the valve spring causes the washer to clamp the jaw members into locking engagement with the groove.

However, when the spring has been compressed and the washer raised on the valve stem by means of the lifter, the valve cannot be removed from its place because the jaw members will engage the lock in the groove as soon as the valve stem is raised to the degree in which the lifter has compressed the spring.

As a solution of this difficulty I have invented a novel tool which is used in connection with the lifter for spreading or retracting the jaw members so that the valve stem will slide readily through the same.

In general my improved tool comprises a metal bar whose end is bifurcated and the bifurcated portion bent at substantially right angles, so as to be introduced between the fork of the lifter and to spread the jaw members, thus holding them from engagement with the stem.

For convenience I bifurcate and bend both ends of the jaw, making the tool double-ended and give one of the bifurcations a greater interior width than the other so as to accommodate different diameters of valve stems.

In the accompanying drawings, wherein I have illustrated a practical embodiment of the principles of my invention, Fig. 1 is a view partially in section showing my novel tool in use to spread the jaw members;

Fig. 2 is a bottom plan view of the same; Fig. 3 is a perspective of the tool; Fig. 4 is a detail showing a portion of the valve stem.

Referring to the drawings, 1 represents the valve seat; 2 the head of the valve, and 3 its stem.

The stem 3 extends through the back wall 4 of the valve chamber, and has mounted thereon the helical spring 5 which is compressed between the wall 4 and the spring washer 6 which is held on the stem by its jaw members 7 which engage and lock in the circumferential groove 8 on the lower end of the stem 3.

The washer 6 is of frustro-conical shape so that the end of the spring 5 telescopes down over it, the end of the spring seating in an annular trough 9 which forms the base of the washer.

The jaw members 7 are arcuate in shape and are preferably two in number, surrounding the stem and so contoured that when the washer is thrust downwardly by the spring the arcuated lower edges of the jaw members will be wedged into the groove 8, as shown in Fig. 4.

The upper ends of the jaw members are provided with outwardly bent ears 10 to prevent their accidental disassemblage from the washer, but permitting their limited movement relative to the washer.

In Fig. 1 I have shown the spring compressed and the washer raised by the fork 11 of a valve lifter inserted under the washer.

Any type of lifter may be employed for that purpose, such as that which forms the subject matter of Letters Patent No. 1,586,835, issued to me on June 1st, 1926.

Experience has demonstrated that if, after the spring is compressed and the washer raised, disengaging the jaw members from the groove, the valve is lifted, as soon as the groove 8 reaches the jaw members, the latter will engage the groove and prevent the removal of the valve.

Much difficulty has been experienced and time and labor wasted in attempting to remove this type of valve. To solve this problem I have invented the auxiliary tool shown in the drawings and comprising a rel-

atively short flat metal bar 12 of convenient width to be grasped in the hand and having one or both ends, preferably both ends, bifurcated and bent at substantially right angles to the body of the bar.

5 Where both ends of the bar are bifurcated and bent, the bends should be in opposite directions for convenience in use.

Then at each of the ends of the bar a pair 10 of substantially parallel bent fingers 13 are provided.

After the spring has been compressed and the washer and jaw members raised off the groove by means of the lifter, as shown in 15 Fig. 1, my tool is employed, with the fingers 13 of one end of the tool straddling the valve stem and disposed at right angles to the fork 11 of the lifter.

The fingers are then forced upwardly be- 20 tween the adjacent edges of the jaw members 7, thus spreading the latter apart, so that the valve stem may be drawn out with the valve.

The ends of the fingers are tapered or thinned to facilitate their insertion between 25 the jaw members.

With the use of a valve spring lifter and my auxiliary tool, the valves of this type of engine may be removed speedily and conveniently.

30 To enable the tool to be used with different diameters of valve stems the space between the fingers 13 at one end of the tool may be wider than at the other end thereof.

What I desire to claim is:—

35 A valve lifting tool consisting of a bar of metal of uniform width throughout and having its ends bent in opposite directions from the body of the bar, said ends being slotted to provide a pair of spaced legs at each end, the 40 slots extending toward the center of the bar in the unbent portion thereof, said legs having parallel inner faces and the remaining faces of the legs being convergent to the extremities thereof.

45 Signed at Pittsburgh, Pa., this 20th day of August, 1928.

PHILIP PALMGREEN.
